UNITED STATES PATENT OFFICE.

FREDERICK M. TURCK AND BRUCE CLARK WHITE, OF NEW YORK, N. Y.

SHEET-FEEDING DEVICE FOR PRINTING-PRESSES.

1,306,087.

Specification of Letters Patent. Patented June 10, 1919.

Application filed August 29, 1917. Serial No. 188,764.

To all whom it may concern:

Be it known that we, FREDERICK M. TURCK and BRUCE C. WHITE, citizens of the United States, and residents of New York, 5 in the county of New York and State of New York, have invented certain new and useful Improvements in Sheet-Feeding Devices for Printing-Presses, of which the following is a specification.

10 This invention relates to improvements in printing presses in which sheets are fed to a sheet carrier and particularly to such a type of printing press as is shown and described in Patent No. 1,146,039, dated

15 July 13th, 1915, issued to Frederick M. Turck.

The object of our invention is to provide operative means for gripping a sheet which has been previously positioned by hand or 20 by automatic means, advancing said sheet into position to be gripped by grippers upon a moving sheet carrier and transferring the sheet thereto, then returning the sheet gripping and advancing mechanism to its normal position to receive another sheet.

Another object of our invention is to provide means for feeding sheets at regular intervals into successive sheet carriers as for 30 instance into every third carrier without interfering with the passage of the two intervening carriers in one or both of which a sheet may already be gripped.

Another object of our invention is to provide a sheet feeding means which shall be in 35 actual engagement or contact with the sheet-carrier at the instant the sheet is transferred to the latter in order that each sheet shall be accurately positioned therein irrespective of the lost motion or wear of the operating 40 parts or gearing.

The invention also includes certain details of construction hereinafter set forth.

In describing the invention in detail reference is had to the accompanying drawings 45 forming a part of this specification, wherein like characters of reference are used to designate corresponding parts throughout the several views and in which:

Figure 1 is a general side elevation of a 50 printing press with the feed mechanism attached. Fig. 2 is a plan view of the same. Fig. 3 is a sectional elevation of the feed mechanism on line 1—1 of Fig. 13, showing the parts in the relative positions they 55 would assume at the instant of gripping the sheet. Fig. 4 is similar to Fig. 3, except

that the parts are here shown as having advanced to the position in which the sheet is being transferred to the sheet carrier. Fig. 5 is an enlarged sectional view similar to 60 Fig. 4. Fig. 6 is an enlarged detail section on line 4—4 of Fig. 14 with the parts in the position assumed immediately before transferring the sheet to the carrier. Fig. 7 is a plan view taken on line 3—3 of Fig. 13. Fig. 65 8 is an enlarged detail of the front-registering guide. Fig. 9 is a section of the same upon line 5—5 of Fig. 8. Fig. 10 is an end elevation of the same. Fig. 11 is a plan view of one end of the front-registering 70 guide in partial section on line 6—6 of Fig. 10. Fig. 12 is an enlarged section of the nipper-bar on line 7—7 of Fig. 8. Fig. 13 is a transverse section of the driving end of the feed device on line 2—2 of Fig. 3. Fig. 75 14 is an elevation of a part of the feed-arm and connections as viewed from the feed-board.

Referring to Figs. 1 and 2 numeral 1 designates the bed-plate of the press upon 80 which are bolted the frames 2 and 3. In these frames bearings are provided for the two plate cylinders 4 and 5 and the impression cylinders 6 and 7.

For imparting motion to the printing cylinders a shaft 8 is mounted in bearings formed on the rear frame 3 and in the floor-stand 9, the shaft being provided with a power-pulley 10 and a driving pinion 11, the latter engaging the intermediate gears 12, 90 12. The latter engage the intermediate gears 13, 13 which in turn engage the gearings 14, 14 secured upon the impression cylinders 6 and 7. Gear rings 15, 15 are secured one to each plate cylinder 4 and 5 and 95 engage with the gearings 14, 14 of the impression cylinders 6 and 7, the gears being of such proportions that the several cylinders of the printing couples will be rotated at a common rate of speed.

For advancing the work to be printed a sheet-carrier is provided, composed of oppositely-disposed annular toothed carrier rings 16, 16 rigidly connected together by seven cross-braces or sheet-carriers 17. The carrier rings are geared to the cylinders 6 and 7 by gear-rings 18.

The particular construction herein shown is that of a printing press, adapted to print 4 colors in one operation. A sheet is fed for 110 each rotation of the cylinders or for every third sheet carrier, hence it is required that

the feeding device be arranged to grip a sheet, advance it to a sheet carrier, introduce it therein, release it as the carrier grippers seize it and then retire to a position out of 5 the way of succeeding carriers until the next carrier appears into which a sheet is to be fed. To effect these movements we preferably employ the following mechanism:

A gear 19, keyed to the counter shaft 20 is 10 mounted to intermesh with the gear-ring 14 of the impression cylinder 7. The shaft 20 is journaled in the flanged sleeve 21 which latter is secured through an opening 22 in the arch-frame 23 by a nut 24. To the outer 15 end of the shaft 20 is keyed a pinion 25. This latter meshes into the cam-gear 26, keyed to the cam-shaft 27. The gears 19 and 26 and pinion 25 are further secured to their shafts by nuts 28. The cam-shaft 27 is 20 journaled in a bushing 29 in the frame 23 and extends to the opposite side of the press where it is also journaled in a bushing 30 in the arch frame 31. The gearing is so proportioned that the cam-shaft 27 will make 25 one revolution for each revolution of the printing cylinders.

A cam 32 is secured by bolts 33 to the gear 26. Upon the surface of this cam rides a friction roller 34 mounted to revolve freely 30 upon the pin 35 which latter is journaled in the radius-arm 36 and is firmly secured in the spring-rod 37 by the nut 38. The radius-arm 36 is pivotably connected to the arch-frame 23 by a pin 39 secured by the nut 40. 35 The spring-rod 37 extends upward through the eye block 41 in which it is free to slide. The latter is formed with a round shank 42 which is free to rotate in a hole in the rocker arm 43 in which it is retained by the nut 44. 40 Upon a screw-threaded portion of the spring rod 37 are nuts 45 and washer 46; and between this washer and the eye-block 41 is placed a spiral spring 47. Nuts 48 at the upper end of the spring-rod 37 are screwed 45 down against the top of the eye-block 41.

This arrangement of spring permits an adjustment of the operative length of the spring-rod 37 and permits it to yield when necessary as will hereinafter appear.

50 The arm 43 is provided with a hub 49 in which is tightly fitted and keyed the rock-shaft 50. This rock-shaft is mounted in bearings 51 in the arch-frames 23 and 31 secured by caps 52 which are bolted to the 55 arch-frames by screws 53. The arm 43 extends upward and forward for operative connection with the spiral spring 54. The latter thrusts at its lower end against the puppet head 55 of the spring-rod 56 about 60 which it is coiled. The head 55 is bored to fit freely upon the stud 57 which is rigidly secured in the arch-frame 23 by the nut 58. An eye-block 59 is fitted to slide freely along the spring-rod 56 and thereby compress the 65 spring 54. The shank 60 of the eye-block 59

is free to turn in a hole in the upper extension of the arm 43 in which it is retained by the nut 61. A nut 62 retains the head 55 of the spring-rod upon the stud 57. This spring is of sufficient tension to press the 70 roller 34 downward upon the rotating cam 32 at all times except when interrupted as will be described.

The rock-shaft 50 has rigidly keyed to it the rocker-arm 63. This arm is swung forward or to the left in Fig. 4 by the thrust of the spring 54 and is permitted to swing forward at the right time and rate of speed as controlled by the form of the depression 64 in the rotating cam 32—see Figs. 3, 4 and 6. 80 This depression is such as to cause the arm 63 to start to swing forward from its position of rest at the front of the feed board 65, as soon as a sheet-carrier 17 has passed. The arm 63 follows closely after the sheet-carrier, gains upon it, and comes into contact with it, the bearing plates 66 secured upon the swinging arm coming into a combined rolling and sliding contact with appropriately curved abutment surfaces 67 at each 90 end of the sheet carriers 17. The cam surface 64 is slightly relieved to afford this contact. The surfaces 67 are provided upon each of the seven sheet carriers as they will each come into contact with the swinging 95 feed arm in their order of sequence. This forward movement of the swinging feed arm 63 coincides with that of the sheet carrier 17 for a sufficient time to transfer the sheet to the latter whereupon its forward movement 100 is arrested by the return curve of the cam 32 which causes the arm 63 to finally swing to the right to the position shown in Fig. 3.

It is important that the position of the swinging arm 63 be slightly adjustable when 105 in its extreme position to the right, also that its position be taken with great accuracy and independently of wear, or lost motion of other parts. To accomplish this end we have introduced movable stops 68 screwed 110 into the cross frame 69 of the feed table 65. Lock-nuts 70 are provided to secure the stops in their adjusted position. Preferably we provide leather or fiber cushions 71 in the contact face of these stops. To 115 provide for the variable action of these stops it was necessary to introduce the yielding spring 47, which yields only under the action of cam 32 when the movement of the arms 63 is arrested by the stops. Thus it 120 will be seen that extreme nicety of adjustment may be obtained and maintained in the movement of the feed arms. It will also be evident that the spring 47, in unyieldingly transmitting the movement of the arms 63, 125 is provided with a tension considerably exceeding that of the spring 54.

The swinging arms 63 are preferably connected at their lower ends by an integral web 72 of angle section which forms a part of 130

the sheet nipping device, and extends across the machine coextensive with the sheet carriers. Below the web 72 is a clamping-bar 73 of angle section suspended by rods 74 to which bar 73 is firmly secured by nuts 75. Along the front edge of the bar 73 are upwardly projecting pegs 76. A square bar 77 extends between and through the arms 63 in which latter it is guided and confined by the caps 78 while free to move vertically therein. Into this bar the rods 74 are firmly secured by the nuts 79, thus forming a stiff rectangular structure of the bars 73 and 77 and the rods 74. The latter slide freely in holes in the lower ends of the arms 63. Spiral springs 80 encircle the rods 74 and thrust upward upon the bar 77, thus thrusting the pegs 76 against the bottom edge of the web 72 of the swinging feed arm. These pegs are preferably shod with rubber or other substance having a high coefficient of friction; see Fig. 12. The square bar 77 projects beyond the arms 63 at each end and is rounded to form a running fit in a roller 81 at either end. The rollers 81 are engaged by the curved under surface of the arms 82. This curved surface 83 is concentric with the center of rock-shaft 50 when the arms 82 are depressed. The arms 82 are keyed to the shaft 84. One of the arms 82 is extended to the left at 85 and is bored to fit freely upon the shank 86 of the eye-block 87 which latter is retained in the arm 85 by the nut 88. Through this eye-block passes the stem of the cam-rod 89 which is rigidly fixed in the eye-block by the nuts 90. These nuts provide means for adjustment of the movement of the arms 82. The cam-rod 89 is forked to slide upon a loose collar 91 upon the shaft 27, between the cam 92 and the collar 93, both of the latter being firmly secured to the shaft 27. The cam-rod 89 has a projecting roller pin 94 rigidly secured to it by the nut 95. Upon this roller pin a cam-roller 96 is fitted to revolve freely and is in contact with the face of the rotating cam 92. The periphery of the cam 92 is concentric throughout the major part of its surface, having a small portion depressed or flattened at 97. The effect of this depression is to lower the roller 96 and with it the rod 89, thus permitting the arms 82 to rise and with them the square bar 77, rods 80 and clamp-bar 73, thus nipping a sheet of paper at numerous points between the pegs 76 and the lower edge of cross-rail 72, the whole upward movement being effected by the springs 80, limited by the cam 92. This cam is so timed in relation to cam 32 that the sheet will be gripped by the nipping pegs 76 immediately before the feed arm begins to swing forward, and will retain their grip on the sheet until the grippers of the sheet-carrier 17 have closed upon

the edge of the sheet with the parts in the positions shown in Figs. 4 and 5. At all other times the nipping pegs 76 are separated from the lower edge of cross-rail 72 thus permitting the sheet to be drawn freely from the feed board 65 by the sheet carrier 17 while the feed-arm is arrested in its forward movement and returned to its first position, as shown in Fig. 3. The nipping pegs 76 remain open for some time after the feed arm has returned to the position shown in Fig. 3, during which time a new sheet is being fed into the space between the feed arm and the nipping pegs.

To insure the uniform positioning of each sheet when fed into the feed arm we provide two movable and adjustable stops or front-guides in the path of the sheet, against which the adyance edge of the sheet is fed. The front guide consists in a depending finger 98, see Figs. 8 and 9 having preferably a renewable toe-piece 99. The finger is secured to the lower end of the guide-lever 100 by screws 101 in slotted holes 102, permitting vertical adjustment of the finger 98. The lever 100 is fulcrumed on the pin 103 in ears 104 which project from the block 105. The latter is free to be slid along the bar 106 and may be secured in any desired position thereon by the set screw 107 and jam-nut 108. Through the upper part of this block 105 is an adjusting rod 109 having a head 110, through which passes a pin 111. The latter also engages the forked upper end of the guide-lever 100. A spiral spring 112 in a recess in the block 105 tends to press the upper end of the guide-lever outward, while the knurled nut 113 draws it back, whereby the lower end 99 of the lever may be adjustably moved forward or back to increase or decrease the projection of the sheet beyond the nipping pegs 76 for purposes of registry. The knurled nut 113 may be locked by the jam-nut 114.

The bar 106 is fitted to slide up and down in recesses 115 in the arms 63, (see Fig. 11,) and is held therein by cap-plates 116 which are secured to the arms 63 by bolts 117. End-plates 118 are fastened to each end of the bar 106 by screws 119 to prevent its end-wise movement.

The guides 99 must be lowered to the position shown in Fig. 12 when the feed arm is in the position shown in Fig. 3, in order to form stops for the sheet when fed to the guides. At all other times the guides are raised as in Fig. 9 to permit the forward passage of the sheet. To effect this movement we utilize the swing of the feed-arm 63 by hanging the bar 106 from a point eccentric to the center of shaft 50. At each end of the bar 106 is a hanger-block 120 secured by a set screw 121 thereto. Between upwardly projecting lugs 122 is pivotally connected a block 123 upon pin 124.

Through a hole in the block 123 passes the threaded end of a rod 125, provided with nuts 126 above and below said block, to secure the rod therein and to afford adjusting means. At the upper end of rod 125 is formed an eye through which passes a pivot-pin 127. This pin also passes through lugs 128 one on each side of the eye. The lugs are integral with a spanner 129 which is bored to fit freely upon the two shafts 50 and 84 which turn within it but retain it in a fixed position. The pivot pin 124 will therefore describe an arc whose center is pivot 127 while the cross-rail 72 of the swinging arm will describe an arc whose center is the center of shaft 50 thus producing the relative movement of the lower end of the guide into and out of the sheet-path as described. A collar 130 prevents the spanner 129 from moving along the shaft 50.

The sheet-carriers 17 are each provided with grippers operated in any approved manner, as by tumbler arms. These grippers remain open after a sheet has been removed and delivered therefrom, and reach the position shown in Figs. 4 and 5 before closing. The Fig. 6 the parts are in a slightly earlier position with the grippers still open. A tumbler pin 131 for closing the grippers is shown in Figs. 5, 7 and 13.

The feed-board 65 is supported by frames 132 and is provided at its front edge with a metal plate 133 which forms an extension of the feed-board. This plate is notched at 134 for the nipping pegs 76 which rise through said notches when the sheet is nipped. When in the position shown in Fig. 12 an uninterrupted surface is presented upon which the sheet may be fed to the guides.

From the above description it will be seen that one important advantage gained by this device lies in the fact that the feed mechanism is at rest against adjustable frame stops and unaffected by the moving parts when the sheet is being registered and gripped, this insuring a measure of accuracy impossible to obtain or maintain in sheet feeding devices, which are under motion at the instant of gripping the sheet, or in devices in which the sheet is moving at the instant of gripping.

Another advantage gained by this arrangement is the large percentage of time allowed for introducing and registering the sheet. This is important when printing rapidly, as the percentage of sheets missed or inaccurately fed is reduced proportionally as the time allowed for placing the sheet is increased. Another advantage derived from the manner of gripping the sheet herein shown is the accuracy of the gripping movement which is at a right-angle to the plane of the sheet. A grip moving at

any other than a right-angle will often shift a sheet slightly at the instant of gripping contact.

The transfer of the sheet from the feed-arm to the sheet-carrier is effected while both elements are moving at the same rate of speed and in contact with each other and uninfluenced by lost motion of parts or back-lash of gears. The instant or place of transfer need not be fixed with extreme accuracy as the mechanism permits of a slight range in these particulars sufficient to permit the sheet to be gripped in the sheet-carrier before being released by the feed arm.

While the feeding device is herein shown as particularly adapted to feeding sheets to a sheet-carrier it may be modified to adapt it to the feeding of sheets to any other moving element. Various changes may be made as regards its form, construction, arrangement and application without departing from the principle and scope of the invention.

What we claim as our invention and desire to secure by Letters Patent is:

1. In a printing press a gripper-carrying feed arm; sheet-stops or registering guides adjustably mounted upon a vertically movable slide-bar thereon; links from said slide-bar to fixed centers located eccentric to the center of the shaft upon which the fixed arm swings.

2. In a printing press, a rotatable sheet-carrier; a movable sheet-feeder; sheet-guiding means carried by said feeder and arranged to receive a sheet in registered relation while the feeder is at rest; sheet-clamping means carried by said feeder; means for operating said clamping means to clamp a registered sheet while said feeder is at rest; means for withdrawing said guiding means after the clamping action is effected; and means for advancing said feeder and delivering the sheet to said sheet-carrier.

3. In a printing press, a rotatable sheet-carrier provided with bearing or abutment surfaces; a movable sheet-feeder provided with resilient operating means and arranged to clamp the leading edge of the sheets while said feeder is at rest; and means for advancing said sheet-feeder at a speed exceeding that of said sheet-carrier and engage the sheet-feeder with the abutments thereof for the delivery of the sheets of the sheet carrier.

4. In a printing press, the combination of a fixed feed-table provided with adjustable stops; a sheet-feeder arranged to receive a sheet from said feed-table; means adapted to effect a yielding engagement between said feeder and the adjustable stops of said feed-table to receive the sheet; and means for delivering the sheet from said feeder.

5. In a printing press, the combination of a fixed feed-table provided with adjustable stops; a sheet-feeder arranged to receive a sheet from said feed-table; register 5 guides carried by said feeder; means adapted to effect a yielding engagement between said feeder and the adjustable stops of said feed-table to receive the sheet; and means for delivering the sheet from said feeder.
- 10 6. In a printing press, the combination of a fixed feed-table provided with adjustable stops; a sheet-feeder arranged to receive a sheet from said feed-table; a sheet-carrier arranged to receive a sheet from 15 said feeder; means adapted to effect a yielding engagement between said feeder and the adjustable stops of said feed-table to receive the sheet; and means for delivering the sheet to said carrier.
- 20 7. In a printing press, the combination of a fixed feed-table provided with adjustable stops; a sheet-feeder provided with registering guides and arranged to receive a sheet from said feed-table; a sheet-carrier arranged to receive a sheet from said 25 feeder; means adapted to effect a yielding engagement between said feeder and the adjustable stops of said feed-table to receive the sheet; and means for delivering the sheet to said carrier.
- 30 8. In a printing press, the combination of a fixed feed-table provided with adjustable stops; a sheet-feeder arranged to receive a sheet from said feed-table; a sheet-carrier arranged to receive a sheet from said feeder; means adapted to effect a yielding engagement between said feeder and the adjustable stops of said feed-table to receive the sheet; and means adapted 35 to effect a yielding engagement between said feeder and said carrier while the latter is in motion to deliver the sheet thereto.
- 40 9. In a printing press, the combination of a fixed feed-table provided with adjustable stops; a sheet-feeder provided with registering guides and arranged to receive a sheet from said feed-table; a sheet-carrier 45 arranged to receive a sheet from said feeder; means adapted to effect a yielding engagement between said feeder and the adjustable stops of said feed-table to receive the sheet; and means adapted to effect a yielding engagement between said feeder and said carrier while the latter is in motion to deliver the sheet thereto.
- 55 10. In a printing press, the combination of a sheet-carrier; an abutment formed on said carrier; a sheet-feeder arranged to deliver a sheet to said carrier while the latter is in motion; and means adapted to 60 effect a yielding engagement between said feeder and the abutment formed on said carrier.
11. In a printing press, the combination of a printing couple; a sheet-carrier arranged to deliver a sheet to said couple at a speed common with the printing speed; a sheet-feeder arranged to deliver a sheet to said carrier; a fixed feed-table provided with adjustable stops; means adapted to 65 effect a yielding engagement between said feeder and the adjustable stops of said feed-table to receive the sheet; and means for delivering the sheet from said feeder to said carrier.
- 70 12. In a printing press, the combination of a printing couple; a sheet-carrier arranged to deliver a sheet to said couple at a speed common with the printing speed; a sheet-feeder arranged to deliver a sheet 75 to said carrier; a fixed feed-table provided with adjustable stops; means adapted to effect a yielding engagement between said feeder and the adjustable stops of said feed-table to receive the sheet; and means adapted to effect a yielding engagement between said feeder and said carrier while the latter is in motion to deliver the sheet thereto.

Signed at New York, in the county of 90
New York and State of New York, this 25th
day of August, A. D. 1917.
